CHARACTER BEARING HOLDER

Charles F. Mitchel, Rochester, N. Y., assignor to
 Bastian Brothers Company, Rochester, N. Y., a
 corporation of New York

Application May 5, 1942, Serial No. 441,855

1 Claim. (Cl. 40—1.6)

This invention relates to a holding button for portraits, emblems, symbols and the like.

One object of the invention is to provide a holder for portraits for identification or for other purposes or for the display of emblems, symbols and the like to be carried or worn by the user and which includes an enclosing casing composed preferably of plastic material and in which the front or the front and back is transparent.

Another object of the invention resides in the provision of a simple, durable, and inexpensive display or other button composed of any suitable material and which includes an enclosing casing provided with an internal reinforcing member to which and to the casing a garment attaching means is anchored against accidental disconnection.

With the above and other objects in view, the invention consists in the combination and arrangement of elements illustrated in the accompanying drawing and described in the following specification, it being understood that changes may be made in matter of shape, size, and proportions of the various elements without departing from the spirit of the invention or sacrificing any of the advantages thereof, so long as departure is not made beyond the scope of the appended claim.

In the drawing:

Figure 1 is a front face view of the invention.

Figure 2 is an enlarged sectional view on the line 2—2 of Fig. 1.

Figure 3 is a rear view.

Figure 4 is an exploded perspective view.

Figure 5 is a fragmentary view showing the slots in the back of the holder.

Referring now to the accompanying drawing, the reference characters A and B indicate similarly formed front and back members, respectively, composed preferably, of plastic material, either transparent or opaque, but as shown the front member A is composed of transparent material while the back member is composed of opaque material.

The front member is illustrated as of disk form 1 provided with a peripheral flange 2, forming a cup-shaped front member. The back member includes a disk portion 3 and a peripheral flange 4, forming a cup-shaped member. These two similarly formed front and back members are adapted to telescope with each other with their flanges overlapping and when in overlapping relation sealed together either by tight fit or by any suitable means, forming an inner recess or pocket C.

The pocket C receives a picture mat or mask 5 of disk formation and of thin paper or the like and lies against the inner face of the transparent front member A and has therein an opening 6 of any suitable configuration for the display therethrough and through the transparent front member of a portrait or other figure or emblem, symbol or the like carried on a thin disk element 7.

10 A relatively thick or stiff solid disk 8 lies in the recess or pocket C behind the thin disk element 7 therebetween and a metal disk 9 lying flush against the inner face of the back member B, to maintain the thin disk 7 and the mat or mask 5 together with the mat or mask flush against the inner face of the front transparent member A.

The article thus far described might well be used as a pocket piece, but in order that the article may be securely fastened to a garment, I attach to the back member B and to the aforesaid internal metal plate 9 a common safety pin D. For instance, before the front and rear members A and B are sealed together to enclose the mat or mask 5, disks 7, 8 and 9, I provide the disk portion 3 of the back member B with oppositely disposed, alining short and long slots 10 and 11, respectively, which are adapted to register with corresponding short and long slots 12 and 13, formed in the aforesaid metal disk 9, in which I mount or anchor the safety pin D.

To accomplish the mounting of the safety pin D on the article, the pointed end 14 of the bill 15 of the pin is inserted outwardly through the registering short slots of the back member and metal disk, carrying the coil 16 of the safety pin into the registering short slots and locating the guard 17 of the safety pin in the registering longer slots when the pointed end 14 of the bill 15 may be received by the guard 17 of the pin with the back element 18 of the pin located adjacent the inner face of the metal disk 9, therebetween and the relatively stiff paste board or other disk 8. The front and back members A and B may then be sealed together and the pointed end of the safety pin inserted in or removed from the guard 17 at will to secure the button to a garment or release it from attachment thereto.

The metal disk 9 reinforces the back member B and it may be secured thereto or lie loose therein so long as the slots thereof may register with the similarly formed slots in the back member for the mounting of the safety pin. The 55 slots of the metal disk and the back member

provide substantial seats for the coil 16 and the guard 17 of the attaching safety pin.

As metal is scarce or difficult to obtain substitutes for metal are in order, and while metal may be employed to provide the casing C, I propose as hereinbefore stated, to use plastic material of various kinds for the production of the casing C. Both faces of the metal disk 9 are flat throughout their entire area. The rear flat face of the metal disk 9 fits against the disk portion of the rear member of the casing, which disk portion is flat throughout its entire area so that the plastic casing is reinforced where the safety pin is attached. The safety pin is straight and the straight intermediate portion 18 of the safety pin fits directly against the front flat face of the metal disk 9. The fitting of the straight intermediate portion 18 directly against the metal disk and the arrangement of the end portions of the safety pin in the slots of the metal disk and the plastic rear member of the casing enables the safety pin to be used without liability of breaking or otherwise injuring the plastic material of the casing.

What is claimed is:

A holder of the character described comprising a casing including a transparent front frame member having a disk portion and a peripheral flange and a back frame member including a disk portion flat throughout its entire 30

area and having a peripheral flange, said frame members being of plastic material connected together at their flanges, a disk shaped mask located within the casing and disposed against the rear face of the disk portion of the front frame member and having an opening, a thin disk element for displaying a portrait or other matter confined within the casing back of the mask and viewable through the transparent frame member and through the opening in the mask, a solid disk fitted against said disk element, a relatively stiff metal disk flat throughout its entire area and disposed within the casing adjacent the inner face of the disk shaped portion of said back frame member to reinforce the latter, the disk portion of said back frame member and said metal disk being slotted to form spaced aligning openings therein, and a straight safety pin having its end portions disposed in the spaced openings of the disk portion of the back frame member and the slotted metal disk with a straight intermediate portion located between the ends of said pin and disposed against the flat front face of said slotted metal disk and the rear face of said solid disk, whereby to anchor the safety pin to the holder and to maintain the metal disk close to the inner face of the back member and thereby reinforce the latter.

CHARLES F. MITCHEL.
